(57) **CLAIM**

The ornamental design for a postal scale as shown and described.

DESCRIPTION

FIG. 1 is a perspective view of a postal scale showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the postal scale where the postal scale is in an open state.

The broken lines in the drawings depict portions of the postal scale that form no part of the claimed design.
